7 Claims. (Cl. 315—8.5)

This invention relates to electronic counters and particularly to electronic counters using multi-position magnetron beam switching tubes.

A magnetron beam switching tube is an electron discharge device which has a central cathode and a plurality of groups of electrodes surrounding the cathode, each group of electrodes comprising a position to which an electron beam may flow from the cathode and from which an output signal may be derived. Each group of electrodes includes a target electrode which is adapted to receive an electron beam and produce an output signal therefrom, a spade electrode which serves to form and hold an electron beam on its associated target electrode, and a switching electrode which is used to switch an electron beam from one position to the next. The tube also includes permanent magnet means providing a longitudinal magnetic field which operates with electric fields within the tube to control the flow and switching of an electron beam. The orientation of these fields urges an electron beam in a characteristic direction with respect to each group of electrodes, and this direction is known as the leading direction.

There are many circuits known for using a magnetron beam switching tube as a counting device, and these circuits are generally satisfactory. However, in each of these circuits, the counting speed of the beam switching tube has a characteristic upper limit which is determined generally by the time required to (1) move an electron beam from one position and lock it in at the next position, and (2) return the spade electrode at the one position to normal operating potential so that it can properly perform its function when the beam again returns to its position. The speeds at which these operations take place is affected to a great extent by spade interelectrode capacity.

Accordingly, the principles and objects of the present invention are directed toward the provision of an improved high speed electronic counter circuit using a multi-position magnetron beam switching tube as the basic counting unit thereof.

Briefly, the circuit of the invention utilizes a magnetron beam switching tube of the general type described above in a circuit in which means are provided (1) for causing an electron beam to switch from one position, known as the J position, and lock in at the next position, known as the J+1 position, and (2) for causing the spade electrode at the J position to recover to normal operating potential—these operations occurring at high speed. In one embodiment of the invention, all of the spade electrodes are clamped at their operating potential which may be higher than the normal spade operating potential, as taught in the prior art. With the spade electrodes thus clamped, higher-than-normal current may flow to a J position and higher-than-normal leakage current may flow to a J+1 spade without causing undesired switching of an electron beam to the J+1 position. This J+1 current, in effect, primes the J+1 spade for the next desired switching operation. A high-speed driving source is used to trigger each switching step. Thus, operation (1) above is achieved. Operation (2) is achieved by means of a source of constant current which is coupled to each spade electrode and which causes a J spade to recover rapidly to normal operating potential after a beam has switched to the J+1 position.

2

In another embodiment of the invention, the spade electrodes are clamped at operating potential as described above and a relatively large J+1 leakage current flows and primes the J+1 spade. The spade electrodes are 5 arrayed in two sets, with adjacent spades being in different sets. A high-speed driver is coupled to each set of spades and is adapted to apply alternately relatively high and relatively low potentials to the sets of spade electrodes. The operation of this driver in combination with the priming of the J+1 spade provides the desired high-speed operation.

The invention is described in greater detail by reference to the drawing wherein:

FIG. 1 is a schematic representation of a circuit embodying the invention;

FIG. 2 is a schematic representation of a portion of the circuit of FIG. 1;

FIG. 3 shows typical current-voltage characteristics curves of J and J+1 spade electrodes and a typical spade 20 load line for the circuit of FIG. 1;

FIG. 4 is a schematic representation of a modified circuit embodying the invention;

FIG. 5 is a schematic representation of a portion of the circuit of FIG. 2; and

FIG. 6 shows typical current-voltage characteristic curves of J and J+1 spade electrodes and typical spade load lines for the circuit of FIG. 2.

The circuits described below are particularly suitable for use with the various commercially available magnetron beam switching tubes such as the type 6700 tube or the Burroughs type BX-1000 switch. In actual construction, a magnetron beam switching tube is cylindrical in form, but it is shown schematically in linear form as tube 10 in FIG. 1. The tube 10 includes an envelope 12 which contains a central longitudinally elongated cathode 14 and ten groups of electrodes spaced radially equidistantly from the cathode and surrounding the cathode. For simplicity, only five groups of electrodes are shown numbered "0," "1," "2," "8," and "9." Each group of electrodes includes a generally U-shaped elongated spade electrode 16 and a generally L-shaped target electrode 18 positioned so that each target occupies the space between adjacent spade electrodes. Each spade electrode serves to form and hold an electron beam on its corresponding target electrode. A generally rod-like switching electrode 20 is also included in each group of electrodes and is positioned between each target electrode and the adjacent spade electrode. The switching electrodes are known as switching grids. The shield electrodes which are employed in the BX-1000 switch are not shown. Suitable means is also included in tube 10 for providing an axial magnetic field which is utilized in conjunction with electric fields within the tube to form an electron beam and to switch a beam from one group of electrodes to the next. 55 The direction in which the beam is urged, that is, clockwise or counterclockwise, is always the same and is determined by the orientation of the electric and magnetic fields. The direction in which a beam is urged is called the leading direction.

Briefly, in operation of tube 10, electrons emitted by the cathode are retained at the cathode if each of the spades, targets and switching grids carries its normal operating electrical potential. When a spade experiences a suitable lowering of its potential, an electron beam is formed and directed to the corresponding target electrode. The electron beam may be switched from one target electrode to the next by suitably altering the electrical potentials of a spade or switching grid. Under normal operating conditions, whenever electrode voltages are such that a beam might be supported at several positions, the beam switches to the most leading position and locks in at this position.

In the circuit of FIG. 1, the cathode 14 is connected to a source of reference potential such as ground. A source 26 of positive pulses for clearing the tube 10 is coupled to cathode 14, and a similar source 30 of negative reset pulses is coupled to the "0" spade, that is, the spade electrode 16 at the "0" position. Beam clearing and reset circuits for magnetron beam switching tubes are well known and need not be described in detail. The target electrodes 18 are each connected through a suitable load resistor 32 to a common target bus 38 which is coupled to a positive D.C. power supply V_t . In addition, an auxiliary output tap 44 is provided at each target for connection to a utilization device such as an indicator tube, a printing mechanism, or the like.

The switching grid electrodes 20 are connected in two sets, with the grids at the even-numbered positions in one set and the grids at the odd-numbered positions in another set. Each set of grids is connected to a source V_g of positive bias potential and to one of the outputs of a high-speed flip-flop circuit 46.

According to the invention, each spade electrode 16 is connected to the anode of a clamping diode 50, the cathode of which is connected to a bus 54 which is coupled to a positive D.C. power supply V_s . Each spade is also connected through a suitable relatively large load resistor 58 to a bus 62 which is connected to another position, and the adjacent leading position is designated larger than V_s . Source V_{ss} and resistor 58 are selected to provide a constant current source for the spade electrodes. In one suitable operative arrangement, V_s is about 60 volts, V_{ss} is about 1000 volts, resistors 58 are about 1 megohm, V_t is about 80 volts, and V_g is about 20 volts.

In the circuit of FIG. 1, the tube 10 operates as a counter by switching an electron beam from position to position under the control of the flip-flop circuit 46. An output current flows from each position to which the electron beam flows. A position or group of electrodes to which an electron beam is flowing is designated the J position, and the adjacent leading position is designated the J+1 position. In the operation of a beam switching tube, it is known that an electron beam flowing to a group of electrodes has a certain cross-sectional area and density, and, if a certain maximum density and area is exceeded, leakage electrons flow to the adjacent leading J+1 position. The spade electrode at the J+1 position receives the leakage current, and in typical prior art operation, its potential is gradually reduced to a potential at which involuntary switching of the entire beam to the J+1 position occurs. Thus, in the past, the current in the beam had to be limited to a relatively small value.

The present invention permits the use of electron beams many times greater than in the prior art without involuntary switching occurring.

In operation of the circuit of FIG. 1 and referring to the portion thereof shown in FIG. 2, it is assumed that an electron beam is flowing to one position, the J position, and the beam is to be switched to the adjacent J+1 position. With a beam flowing to the J position, at all of the other positions, current flows from the V_{ss} supply through the spade resistors 58 and the diodes 50 to the V_c supply. This current serves to clamp all of the spade electrodes except J spade at positive operating potential V_c . At the J+1 position, current I splits into two portions, I_d which flows through diode 50 and I_s which flows through the spade electrode. Current I_s is leakage current which is derived from the electron beam at the J position. Since the J+1 spade is clamped at positive potential V_c , it can accept considerably greater leakage current than in prior art operation without its potential being lowered and without its causing undesired switching of an electron beam. Thus, the current to the J position and the resultant output current from the J target can be considerably increased over that possible in the prior art. As an example, 400 microamperes or more

can be tolerated in the J+1 circuit of the invention, whereas, in the prior art, this current was generally limited to about 10 microamperes. In addition, the J current may be about 8 milliamperes compared to 3 milliamperes in prior art operation.

In FIG. 3, are shown typical static and dynamic current-voltage characteristic curves for the J spade and for the J+1 spade, respectively, and the load line for the spade resistors 58. Since the spade resistors are comparatively large, the load line is relatively flat. The load line intersects the X-axis at point A and the static characteristic J curve at two points B and C. The dynamic J+1 and static J characteristic curves very nearly coincide in the vicinity of point C. The various currents which flow at the J+1 position are indicated. In effect, the large leakage current I_s which flows in the J+1 spade prebiases this spade and primes it for performing its function when the beam is switched from the J position to the J+1 position.

20 When it is desired to switch the electron beam from the J to the J+1 position, a negative switching pulse is applied by the flip-flop 46 to the switching electrode 18 at the J position. The actual switching of the electron beam to the J+1 position occurs more or less conventionally. 25 However, the speed with which the J+1 spade charges and locks the beam in position is increased by the high J+1 spade leakage current and the primed condition of the J+1 spade. In addition, since the J spade is connected to the constant current source, comprising power supply V_{ss} and resistor 58, the J spade discharges rapidly and linearly, and returns to normal spade potential V_c rapidly. Thus, the J spade is quickly prepared for the return of the electron beam as it completes its counting 30 cycle. This sequence is repeated each time the beam moves from one position to the next in tube 10.

A modification of the invention shown in FIG. 4 operates by means of spade switching rather than grid switching, as in FIG. 1. In spade switching, the switching pulses which drive the beam switching tube 10 are applied to the spade electrodes 16, rather than the switching electrodes 20. In the circuit of FIG. 4 including tube 10, the target electrodes 18 and their connections are not shown since they may be the same as in FIG. 1. The switching electrodes 20 are arranged to set a relatively high level of J+1 leakage current, and, in one suitable arrangement, they are connected together and to cathode potential which, in this case, is ground.

According to the invention, the spade electrodes 16 are arranged in two sets, with the even-numbered electrodes in one set and the odd-numbered electrodes in the other set. The even-numbered electrodes are connected through normal spade load resistors 74 of about 150,000 ohms to a bus 78 which is connected to one output terminal 80 of a flip-flop 82, and the odd-numbered spade electrodes are similarly connected through normal load resistors 74 to a bus 84 which is connected to the other output terminal 86 of the flip-flop. The flip-flop 82 has a suitable high speed of operation. Each spade electrode 16 is also connected to the anode of a clamping diode 90, the cathode of which is connected to a bus 94. The bus 94 is coupled to a positive D.C. power supply, V_c , the clamp voltage for the spades 16. Voltage V_c is always below the potentials applied to buses 78 and 84 by the flip-flop to provide the desired clamping action. Typically, in the circuit of FIG. 4, V_c may be ground potential, and the flip-flop outputs may alternate between about 20 volts and about 80 volts.

In the circuit of FIG. 4 (FIG. 5), with a beam in the J position, current I flows through the J+1 spade load resistor 74 and splits into clamp current I_d which flows through diode 90 and spade leakage current I_s which flows through the J+1 spade. As set forth above, the switching grids 20 are arranged so that the J+1 leakage current I_s is relatively large. Again, since I_s may be large, the current to the J position may be large. With a beam

in the J position, the flip-flop 82 is in such a state, and it is so designed, that a first low potential is present on the J spade and bus 78 and a second higher potential is present on the J+1 bus 84. The J+1 spade, and all of the spades except the J spade, are clamped at potential ⁵ V_c .

FIG. 6 shows the typical static and dynamic current-voltage characteristic curves for the J and J+1 spades, respectively. FIG. 6 also shows that the circuit of FIG. 4 operates with static J and dynamic J+1 load lines which ¹⁰ are parallel to each other and intersect the X-axis at different places, A and A', determined by the two flip-flop output potentials. As in FIG. 1, the relatively large J+1 leakage current I_s primes or prebiases the J+1 spade and prepares it for the switching operation and for its function ¹⁵ of locking the beam in position.

The switching operation is initiated by a change in state of the flip-flop, and, when this change occurs, the potentials on the buses 78 and 84 are quickly reversed. At this time, the bus 84 assumes the low potential, and the bus 78 ²⁰ assumes the higher potential. Thus, the load lines are switched, and the J+1 spade, which is in an unstable state due to the leakage current I_s , quickly moves to stable point C, and the beam is locked in the J+1 position. At the same time, the J spade quickly returns to its normal operating potential V_c under the influence of the relatively high potential on bus 78. This cycle of operation is repeated each time the flip-flop changes state, and, for all practical purposes, the counting speed of tube 10 may be as high as ²⁵ about 10 megacycles.

The present invention provides a counter which is relatively simple and inexpensive and which operates at speeds of at least 10 megacycles. This speed is at least five to ten times higher than speeds which were readily attainable in the past. In addition, output currents about three ³⁵ times greater than in the past are obtainable.

What is claimed is:

1. An electronic counter circuit including a magnetron beam switching tube having an electron-emitting cathode and a plurality of groups of electrodes, ⁴⁰

each comprising a position to which an electron beam may flow and from which an output signal may flow; a position to which an electron beam is flowing being designated the J position and the adjacent leading position being designated the J+1 position; each group of electrodes including a target electrode which receives an electron beam and produces an output signal therefrom, ⁴⁵

a spade electrode which holds an electron beam on its associated target electrode, ⁵⁰

and a switching electrode which serves to switch an electron beam from one group of electrodes to the next; ⁵⁵

clamp means coupled to each of said spade electrodes for clamping each spade at a first normal operating potential at all times except when an electron beam is flowing to it, ⁶⁰

said clamp means thus allowing considerable leakage current to flow to a J+1 spade electrode without switching an electron beam thereto from the J spade; and relatively high voltage supply means coupled to each of said spade electrodes for quickly returning a J spade to normal operating potential after an electron beam has left it. ⁶⁵

2. An electronic counter circuit including a magnetron beam switching tube having an electron-emitting cathode and a plurality of groups of electrodes, ⁶⁵

each comprising a position to which an electron beam may flow and from which an output signal may flow; each group including a target electrode which receives an electron beam and produces an output signal therefrom, ⁷⁰

a spade electrode which holds an electron beam on its associated target electrode, ⁷⁵

and a switching electrode which serves to switch an electron beam from one group of electrodes to the next; ⁷⁵

electron beam from one group of electrodes to the next;

clamp means coupled to each of said spade electrodes for clamping each spade at a first normal operating potential at all times except when an electron beam is flowing to it,

said clamp means thus allowing considerable leakage current to flow to a J+1 spade electrode without switching an electron beam thereto from the J spade; and a relatively constant current source coupled to each of said spade electrodes for causing rapid charging of the J spade capacitance immediately after an electron beam has switched to the J+1 spade electrode, the J spade thus being quickly returned to normal operating potential.

3. An electronic counter circuit including a magnetron beam switching tube having an electron-emitting cathode and a plurality of groups of electrodes,

each comprising a position to which an electron beam may flow and from which an output signal may flow; each group including a target electrode which receives an electron beam and produces an output signal therefrom,

a spade electrode which holds an electron beam on its associated target electrode,

and a switching electrode which serves to switch an electron beam from one group of electrodes to the next;

diode clamp means coupling each of said spade electrodes to a source of normal operating potential therefor;

a constant current power source coupled to each spade electrode for quickly returning a J spade to normal operating potential after a beam has left it;

means coupled to said switching electrodes for causing a relatively large leakage current to flow to a J+1 spade when an electron beam is flowing to a J spade, ⁴⁰ said diode clamp means preventing undesired switching of the electron beam due to said leakage current.

4. The circuit defined in claim 3 and including a flip-flop circuit coupled to said switching electrodes for causing said switching electrodes to switch a beam from position to position in said tube.

5. The circuit defined in claim 3 wherein said constant current source comprises a relatively high D.C. potential source and a relatively large spade load resistor coupled between said potential source and each spaced electrode.

6. An electronic counter circuit including a magnetron beam switching tube having an electron-emitting cathode and a plurality of groups of electrodes,

each comprising a position to which an electron beam may flow and from which an output signal may flow; each group including a target electrode which receives an electron beam and produces an output signal therefrom,

a spade electrode which holds an electron beam on its associated target electrode,

and a switching electrode which serves to switch an electron beam from one group of electrodes to the next;

means coupled to all of said switching electrodes for causing relatively high leakage current to flow to J+1 position when an electron beam is in the J position;

means clamping all of said spade electrodes at a first potential which comprises a normal operating potential therefor and which allows said high leakage current to flow to a J+1 spade electrode without switching an electron beam thereto from the J spade; said spade electrodes being connected in two sets with every other spade being in the same set; a flip-flop circuit;

each set of spade electrodes being coupled to one of the outputs of said flip-flop circuit whereby adjacent spade electrodes are successively at relatively low and rela-

5 relatively high potentials each time that the flip-flop changes state, each change of state of the flip-flop causing a beam to switch quickly from the J position to the J+1 position by the application of a relatively low potential to the J+1 position and a relatively high potential to the J position, said relatively high potential causing the J spade to return quickly to its normal operating potential.

7. The circuit defined in claim 6 wherein all of said

switching electrodes are connected together and to the cathode of the tube, the desired flow of leakage current to a J+1 spade electrode thus being achieved.
